UNITED STATES PATENT OFFICE.

CHARLES E. PIERSON, OF RAYTOWN, MISSOURI.

END-GATE FOR VEHICLES.

SPECIFICATION forming part of Letters Patent No. 687,574, dated November 26, 1901.

Application filed March 5, 1901. Serial No. 49,947. (No model.)

To all whom it may concern:

Be it known that I, CHARLES E. PIERSON, a citizen of the United States of America, residing at Raytown, in the county of Jackson and 5 State of Missouri, have invented certain new and useful Improvements in End-Gates for Vehicles; and I do hereby declare that the following is a full, clear, and exact description of the invention, such as will enable others to make and use the same, reference being 10 had to the accompanying drawings, forming a part of this specification.

The object of my invention, primarily, is to afford an end-gate which may be adjusted in 15 position rearwardly at any desired angle of inclination and when adjusted will prevent the waste resulting from the overflow of the contents of the wagon or vehicle; second, to control automatically the movements of the 20 end-gate in its adjustment to a position above and transverse to the sides of the wagon or vehicle, and, third, to secure automatically the devices controlling the end-gate when the 25 gate is moved from an inclined to an upright or closed position.

The invention consists in the novel construction and combination of parts, such as will be first fully described, and specifically pointed out in the claims.

30 In the drawings, Figure 1 is a broken plan view of the body of a wagon or vehicle, showing the improved end-gate in a closed position and the extension devices upon the sides of the body connected with the end-gate for 35 controlling its movements. Fig. 2 is a side view of the wagon as seen in Fig. 1, showing the end-gate in a closed position and in dotted lines its position when adjusted in a rearward-inclined position. Fig. 3 is a view in perspective of the body of the wagon as in Fig. 1, showing the end-gate in a raised position and supported by the sides of the wagon-body and also showing the position of the 40 gate-controlling devices. Fig. 4 is a view in 45 perspective of an alternate link-joint for the adjusting-rod. Fig. 5 is a detail view of the forward end of the adjusting-rod.

Similar letters of reference indicate corresponding parts in all the figures of the drawings.

Referring to the drawings, A represents an

ordinary wagon box or body, of which a a represent the sides, and a' the bottom, of said body, with which the sides are rigidly connected.

55

B represents the end-gate, which extends in width from the plane of the outer surface of one side a to the plane of the outer surface of the other side a of the wagon-box and in height from the plane of the under side of the bottom a' of the wagon-body upwardly a short distance above the upper edges of the sides a a of said wagon-body.

60

The end-gate B is supported by a transverse bar C, which is rigidly connected with the under side of the bottom a' at the rear end of the wagon-body, a portion c of the upper surface of which bar extends a short distance rearwardly of the rear edge of said bottom. The ends of the bar C extend in length 70 a short distance beyond the planes of the outer surfaces of the sides a a for the purpose herein described.

65

With the vertical edge portions of the end-gate B are rigidly connected the guard-boards 75 b b, which extend at right angles from the end-gate and from the outer surface of said gate forwardly a short distance and overlap the outer surface of the sides a a of the wagon-body when hinged thereto. The guard- 80 boards b b extend in length from the upper edge of the end-gate downwardly a short distance below the lower edge of said end-gate and as far as the under side of bar C, and in the rear edge of said lower end of the guard- 85 boards are notches c' c', cut transversely to said boards, which notches receive the extended ends of bar C, whereby the end-gate is hinged to the body of the wagon.

85

Upon the outer side of the end-gate and 90 extending the width of said gate are stiffening-bars b' b'. With the outer side of the end-gate at a point midway from its upper and lower horizontal edges and connected with said gate by rivets or screws e e are narrow plates E E, the outer ends being drawn to the size of a small rod and extended a short distance in opposite directions beyond the guard-boards b b, and thence bent at right angles and extended close in position 100 to the outer sides of said guard-boards, and also inclined upwardly at an angle to the

95

rear edge of said guard-boards and secured thereto by staples $c^2 c^3$. Upon the ends of the said bent portions of plates E E are loops or links $e^3 e^3$, which extend horizontally in position.

5 F F represent the end-gate controlling or adjusting rods near the outer surface of the sides $a a$, upon the rear end of which rods are loops or links $f f$, which are connected 10 with the links $e^3 e^3$. The rods F F are made of the proper length for the rearward inclination of the end-gates and also the elevation of the end-gate, the forward end of said rods being bent at right angles to the link f , and 15 thence parallel with said rod a short distance to form the hooks $f' f'$, thence bent downwardly at right angles to hooks f' , and thence extended upwardly in the direction of rods F and to a position a short distance from said 20 rods, forming separate hooks $f^2 f^2$.

Upon the outer surfaces of the sides $a a$ of the wagon-body, at a point nearly midway from the bottom a' , in the direction of the upper edges of the sides $a a$, are stationary 25 guide-rods G G, which are arranged horizontally in position and at short distances outwardly from the sides $a a$. One end of the respective rods G extends rearwardly as far as required to limit the play of the adjusting-rod F and in the direction of the guard-board b and is bent at right angles and extended 30 upwardly a slight distance, as at g , thence extended in the direction of the side a of the wagon-body, as at g' , and the end bent in 35 the plane of the side a and secured to the side by the screw or rivet g^2 . The other end of rod G extends forwardly the proper distance circumscribed by the length of rod F from its link connection with the end of gate 40 (when the gate is in a closed position) to the hook f^2 . The said forward end of rod G is bent at right angles and extended downwardly a short distance, as at g^3 , to form the locking-shoulder for hook f' , thence extended 45 in the direction of the side a of the wagon-body, as at g^4 , and bent in the plane of the surface of said side and secured thereto by the rivet or screw g^5 .

When the end-gate B is hinged to the bar 50 C and in an upright or closed position, the hooks $f' f'$ on the adjusting-rods F F are extended over and interlock with the bent portions or shoulders $g^3 g^3$ of the guide-rods G G and the gate is firmly held in position, the 55 forward end of the rod inclining downwardly and obtaining a strong purchase on the end-gate. In this position of the end-gate the guard-board prevents sifting out of the contents of the wagon, such as grain or other 60 fine cereals, which ordinarily escapes in transportation. When it is desired to incline the end-gate rearwardly upon the hinged connection with bar C, the rods F F are raised from the shoulder g^3 and upwardly as far as the 65 hooks $f^2 f^2$ will permit and the said rods given a partial rotation, which movement reverses the position of the hooks $f^2 f^2$, as seen in

dotted lines in Fig. 2, and said hooks are free to move upon the upper sides of rods G G. The end-gate B is then inclined rearwardly the full distance necessary or to a position in which the said hooks come into contact with the bent portion or stop g' at the rear end of rod G, and the end-gate is held from further movement. In the rotation of 70 rod F the link f' turns outwardly upon the link e^3 , engaging with the lower part of said link. Instead of the links e^3 and f I may employ a ball-and-socket or universal joint, as seen in Fig. 4, in which the socket H is secured 80 to the sides $a a$ by the screw h, the adjusting-rod having the ball h' connected therewith. The end-gate B is also permitted a movement upwardly, as seen in Fig. 3, to a position transverse to the sides $a a$ and resting thereon, this 85 adjustment releasing its connection with the bar C and enabling the ready discharge of the contents of the wagon, the position of the end-gate being secured by the rods F F. In an emergency the end-gate may be moved 90 forward and placed flatwise upon the sides, so as to afford a seat for the driver. The rods F F are readily disengaged from the rods G G when the removal of the end-gate is desired 95 and prevents accidental loss thereof when secured to the rods G G. When the end-gate is moved upwardly and forwardly upon its hinged connection with bar C and to a closed position, the rod F is first partially rotated upon its linked connection, so as to turn the 100 hook f^2 downwardly, and permits the hook f' to move along the upper edge of the rod G, and at the forward end of said rod said hook engages automatically with the shoulder g^3 .

Such modifications may be employed as are 105 within the scope of the invention.

Having fully described my invention, what I now claim as new, and desire to secure by Letters Patent, is—

1. The combination with a wagon box or 110 body and with the sides of said body of an end-gate hinged thereto, a gate-adjusting rod, and a universal-joint fastening connecting one end of said rod with the end-gate, guide-rods on the sides of said wagon-body, and reversible hooks upon the other end of said rod. 115

2. An end-gate-controlling device, consisting of an adjusting-rod, a joint-fastening at one end, and separate hooks at the other end integral with said rod, one of which depends 120 below, and arranged transverse to the other, and a guide-rod having bent forward and rear ends, one of which forms a shoulder, substantially as described.

3. The combination with a wagon box or 125 body, and with the sides of said body, of an end-gate hinged thereto, and guard-boards connected with the vertical edge portions of said end-gate, links connected with and extending horizontally from said guard-boards, 130 gate-adjusting rods having links at one end engaging with the links on said guard-board, and separate hooks at the other end of each rod integral therewith, one of which hooks

extends at right angles to the link on the other end of said rod, and the other depending and arranged at right angles to the former hook, horizontal guide-rods upon the sides of said wagon-body, below the plane of the links on said guard-boards, and having their ends bent downwardly at their forward ends to form

shoulders, and also bent inwardly at their rear ends to form stops, and connected with the sides of the wagon-body.

CHARLES E. PIERSON.
